UNITED STATES PATENT OFFICE.

ISAAC J. SEGAL, OF MALDEN, MASSACHUSETTS, ASSIGNOR TO HENRY SISKIND, TRUSTEE, OF BROOKLINE, MASSACHUSETTS.

LOCK.

Application filed May 23, 1921. Serial No. 471,630.

To all whom it may concern:

Be it known that I, ISAAC J. SEGAL, of Malden, in the county of Middlesex and State of Massachusetts, a citizen of the 5 United States, have invented a new and useful Improvement in Locks, of which the following is a full, clear, and exact description, reference being had to the accompanying drawings, forming a part of this specification 10 in explaining its nature.

The invention relates to an improvement in locks and essentially to a coin-controlled lock.

It is among the objects of the invention to 15 provide a coin-controlled lock permitting of the following operations:—retraction of the bolt of the lock from the exterior side thereof by the turning of a knob or handle upon the insertion of a coin which assists in affecting such retraction; by an independent mechanism effecting retraction of the bolt from the rear side of the lock on turning a knob or handle; preventing retraction of the bolt by the turning of either knob or 25 handle from the front or back of the lock and permitting retraction of the bolt under all circumstances from the outer side of the lock by a key-controlled mechanism; preventing the admission of a coin to the operating parts of the lock after a coin has 30 once been inserted and before the release of such coin, all of which operations are found to be very desirable in a lock of the present type.

35 A further object is to provide the lock with a counter capable of automatically registering successive uses of the lock under conditions where a coin is employed for assisting in the retraction of the bolt.

40 In a lock having the aforesaid adaptability it is my further object to provide concise intimately associated or combined mechanisms possessing few wearing parts and any of which parts are easily replaceable; mechanisms, also, that are operable under all 45 conditions of use and which are practically fool-proof. In other words, it is my object to provide a coin-controlled lock of great flexibility especially fitted to perform the 50 purpose or purposes for which it is designed.

The invention can best be seen and understood by reference to the drawings in which—

55 Figures 1 and 2 show in side elevation the interior of the lock casing and various of the

operating mechanisms contained therein, Fig. 2 showing the parts in a different operative position from that shown in Fig. 1, all of which will later be referred to in detail.

60

Fig. 3 is a section on line 3—3 of Fig. 1.

Fig. 4 is a section on line 4—4 of Fig. 1.

Fig. 5 is an inside elevation of the lock casing, the interior mechanism being covered and held in place by a plate carrying 65 the counting mechanism or register later to be referred to.

Fig. 6 is an elevation of the interior of the cover of the casing, and

Fig. 7 shows partly in cross section and 70 partly in plan a detail of construction to which reference will later be made.

The operating parts of the lock are contained within a casing 1 having a cover 2. The casing has a back 1^a, side edge plates 1^b, 75 1^c, respectively, a top edge plate 1^d and a bottom edge plate 1^e. The cover is provided with interior posts 3 by which it is secured to the casing by screws 4 entering from the back. The casing contains a plate 5 which 80 assists in retaining and carrying various of the operating parts. This plate rests upon the ends of posts 6 projecting from the back of the casing and to which the plate is fastened by screws 7.

85

8 represents the head of the bolt and 9 its shank. The bolt operates through an opening 10 in the side edge plate 1^b of the casing and from this edge the head protrudes when the head is in engagement with its keeper (not shown). The shank 9 of the bolt is slidable on the back of the casing and is provided with an end crossbar 10' which engages the interior of the side edge plate 1^c of the casing when the bolt is occupying a 90 retracted position for defining such position. The shank is bifurcated and into the slot 11 thus left extends a short pin or stud 12 from the back of the casing, acting to assist in guiding the shank during the sliding of 100 the bolt. The shank of the bolt is also guided on the lower or under side by fixed guides 13 and above by the lower end of a coin chute 15 fixed to the casing, and to which special reference will later be made. 105 The shank of the bolt is also provided with a flange 16 which engages the interior of the side edge plate 1^b of the casing when the bolt is occupying its extended or engaging position for defining such position. The 110

bolt is yieldingly maintained in a normal engaging or extended position by a spring 17.

The bolt is initially controlled by means 5 of a key-controlled lock. For this purpose a lock 19, preferably of the pin type, is arranged within the cover 2 of the casing adjacent the shank of the bolt. The barrel 20 of the lock 19, turned by a key, is provided with an arm 21 which engages an arm 22 on the shank of the bolt, which extends through a slot in plate 5, the relation of the parts being such that the bolt may be retracted upon turning the key in the lock 15 19 by the engagement of the arm 21 with the arm 22 on the shank of the bolt. The bolt may be thrown into a disengaging position by the key-controlled lock just referred to irrespective of the other operative parts 20 later to be referred to.

Reference will now be made to the mechanism by which the bolt may be thrown into a retracted or disengaging position upon the insertion of a coin. It will first be observed that the top edge plate 1^a of the casing is provided with a slot 24 through which a coin may be inserted. Immediately below this slot is arranged the coin chute member 15, previously referred to, fixed to the casing. The face of this chute member is flush with the inner side of the slot 24 and also with the outer side or face of the shank of the bolt so that a coin inserted through the slot 24 may pass downwardly over the face 35 of the chute member and over the shank of the bolt. The chute member 15 is provided with side edge flanges 25, 26, respectively, the flange 26 being provided with a lateral extension 27. The flanges 25, 26 and extension 27 rise above the face of the chute member 15 a distance about equal to the width of the coin and provide in part a bearing for a plate 29 forming a chute member opposite the member 15 and between 40 which members the coin is directed to pass downwardly over the shank of the bolt as aforesaid.

The chute member 29 consists of the head and body portion of a slide member 30. This member rests and is slidable upon the sides 25, 26 of the coin chute and the extension 27 therefrom. The body of the member extends downwardly over the outer face of the shank of the main bolt and is spaced 55 therefrom to admit of the downward passage of a coin out of the chute over the outer face of the shank and between it and the member 30. When the member is occupying its normal position the rear edge 60 31 thereof lies forward of the plate 10' on the rear end of the bolt shank. On its forward side in the direction of the head of the bolt the member is provided with an arm extension 32 which rests against and 65 is slidable upon another slidable member 33

later to be referred to. At its lower end the member 30 is provided with an inwardly and downwardly projecting foot 34. Projecting from this foot and extending therefrom in the general direction of the head of the bolt is a bar extension 35 which slides upon the back of the casing and between the guides 13 and a guide 36 fixed to the casing. The normal position of the member 30 is defined by the engagement of the edge 37 of the head 29 of the member with one of the posts 6 of the casing and in which normal position the member 30 is yieldingly maintained by the bearing of a spring 38.

In connection with the member 30 attention is directed to an edge 39 with which this member is provided. This edge lies at the junction of the foot 34 with the member and faces the passageway through which the coin drops from the coin chute 85 downwardly over the outer face of the shank of the bolt. As will later be explained, the coin engages this edge during its downward passage, the edge assisting in the retention of the coin until its release. 90

The slideable member 33 is arranged forward of the member 30 in the direction of the head of the bolt and is slideable over the shank of the bolt and the bar extension 35. The member 33 is provided on the inner side thereof with an elongated stud 40 which fits within the slot formed in the bifurcated shank of the main bolt and is guided thereby. The member 33 is also guided during its sliding movement by the guide 36, the member being provided with a flanged edge 41 in engagement with this guide. The portion 42 of the member 33 is the portion over which the arm 32 of the member 30 extends as explained above, and this portion of the member 33 is made of just sufficient thickness to assist in providing for proper spacing of the member 30 in relation to the shank of the bolt, to admit of the passage of the coin. The portion 43 of member 33 is also made of the same relative thickness as the part 42 in order that as the member is moved backward it may slide beneath the lower portion of the member 30. Attention is also directed to the rear edge 44 of the member 33 which faces the opening or slot through which the coin is passing, this edge being complementary to the edge 39 on the member 30 and assists in the retention of the coin during its downward passage, in other words, the coin contacting with the edges 39 and 44 and being initially retained by them. 105

Attention is also directed to the curvature of the edge 44 which is for a purpose now to be referred to. 110

The member 33 is retained to occupy a normally defined position from which position the member is slideable in the general direction of the rear edge of the casing. 115

It is when occupying its normal defined position that the coin will contact with the edges 39 and 44 as aforesaid, the coin initially contacting with the lower portion of 5 the edge 44 as shown in Fig. 1. As the member 33 is moved backward the coin owing to the curvature of the edge 44, will be thrown upwardly and occupy a position substantially as shown in Fig. 2 where the 10 coin is shown lifted out of contact with the edge 39 of the member 30 and into contact with piece 45 loosely arranged on the rear end of the bolt shank and retained by the plate 10' on the end of the shank. As 15 the movement of the member 33 is continued it will, through the interposition of the coin and piece 45, act upon the end bar 10' on the bolt shank and thereby move the bolt when the bar 10' will contact with the 20 rear edge plate 1^c of the casing, which defines the retracted position of the bolt.

The member 33 is positioned and its movement controlled by mechanism connecting with the front or main knob of the 25 lock or door to which the lock is secured, and it is accordingly by turning this knob after the insertion of a coin that the bolt may be moved into its retracted position. Referring to such positioning and controlling mechanism, 46 represents the knob on the front side of the lock and accordingly on the outer side of the door to which the lock is secured. The knob is arranged to turn within a socket 47 on the cover 2 of 30 the casing. The knob carries a shank 48 which fits into and is secured to a hub 49 socketed to turn between the back of the casing and the plate 5. The hub carries an arm 50 which connects with the sliding member 33 by a stud 51 on said member contained within a slot 52 in the end of the arm. The arm 50 is yieldingly held to bear 35 against a post 53 on the casing by a spring 54 and when occupying this position the arm acts to hold the member 33 in its initial operative position above referred to for holding the coin. On turning the knob the arm and member 33 with it will be moved back thereby retracting the bolt through 40 the interposed coin and piece 45 as explained above. On the release of the knob the arm and member 33 will be returned to their original positions by the spring 54 and the bolt will be moved back to its engaging position by the spring 17. The operation does 45 not effect a release of the coin, the coin then continuing to rest on the lower end of the edge 44 of the member 33 and edge 39 of member 30.

Reference will now be made to the means by which the bolt may be retracted and the coin released. This is accomplished by mechanism operated from the inner side of the door to which the lock is secured 50 and comprising a knob 56 having a shank

57 which extends through the back of the casing and fits within a hub 57' socketed to turn between said back and the plate 5. The hub 57' carries an arm 58 which extends upwardly to bear against the front 70 side of the foot 34 of the slideable member 30, the lever being maintained in this position by means of an arm 59 on the hub 57' which bears against the interior of the side edge plate 1^c of the casing. When the 75 knob 56 is turned the arm 58 will be actuated to retract the member 30 which, by its engagement with the end piece 10' on the rear of the bolt shank, will move the bolt into a retracted position. Inasmuch as 80 the member 30 is retracted during this operation and as this is one of the members acting to hold the coin, the coin will accordingly be released to drop into the bottom 85 of the casing.

Another phase of the lock resides in a mechanism for preventing the retraction of the bolt by turning either of the handles 46 or 56. This operation is initially effected by mechanism operable from the inner side 90 of the lock or door to which the lock is secured and comprises a thumb piece 60 having shank 61 fitting within a hub 62 socketed to turn in the back of the casing. The hub 62 carries a finger 63. This finger 95 is in operative engagement with a latch 64, the finger being contained within a socket 65 in the side of the latch. The latch is guided by a headed pin or screw 66 fixed to the casing back, the shank of the screw extending through an elongated slot 67 in the latch. At its upper end the latch is provided with a tongue 68 which lies normally within an opening formed through the guide 36. The forward side edge of 100 the latch is provided with an arm 69. Affixed to the latch is a spring 70 which bears against a fixed stud 70' on the casing. The latch has in it bends or indentations 70², 70³ into which the stud fits as the spring 105 is moved to run over the side of the stud and by which means the latch is yieldingly held in the engaging or disengaging position to which it may be moved. The latch occupies normally a retracted position as 110 shown in Fig. 1. Assuming the bolt to be extended or in its engaging position, the turning of the button 60 operates to turn the finger 63 and thereby through the finger elevate the latch. Thereupon the tongue 68 will pass through a slot 71 formed in the under side of the slide bar 35 secured to the sliding member 30 as aforesaid. The sliding member 30 cannot then be moved for 115 retracting the bolt on turning the knob 56. The engaging position of the latch will also bring the arm 69 on the side thereof into line with a stud 72 on the under side of the lever 50, thereby preventing this lever being thrown backward for retracting the 120 125 130

bolt on turning the knob 46. On moving the latch back to its original position upon turning the thumb piece release will be effected to permit retraction of the bolt by 5 turning either of the knobs 46 or 56.

Further provision is made in the construction of the lock whereby the slot 24 may be closed after a coin has once been inserted and the bolt moved into a retracted position. As 10 previously explained, the initial retraction of the bolt is obtained by turning the knob 46 which acts through the lever 50 to retract the member 33. As the member 33 is retracted, the coin, initially resting on the 15 members 33 and 30, is lifted into contact with the piece 45 on the shank of the bolt, whereupon as the retraction of the member 33 is continued it, through the interposition of the coin and piece 45 bearing against the bar 20 10' on the end of the shank, effects a retraction of the bolt. The piece 45 thus forming one of the operating parts is a piece loosely arranged upon the rear end of the shank of the bolt and is held in place by a stud 74 25 fixed to the member and extending through the slot 11 in the bolt shank, the stud being secured on the under side by a crossbar 75. When the bolt is extended and the parts are occupying their initial operative position 30 permitting of the insertion of a coin, the crossbar 75 on the under side of the piece 45 will have engagement with the arm 76 of a lever pivoted to the back of the casing at the point 77. The other arm 78 of the lever 35 is in operative engagement with a slide bar 79, the end of the lever arm 78 having bearing against a flange 80 on the side of this bar. The slide bar 79 is arranged in the head of the casing just inside the top edge 40 plate 1^d thereof and is movable between this plate and the fixed portion 15 of the coin chute. The slide bar 79 has in it a slot 81. When the parts are occupying the initial position just referred to the bar 79 will then 45 be positioned where the slot 81 in it will be in exact alignment with the slot 24 in the head of the casing thereby permitting of the insertion of a coin. As the bolt is retracted on turning the knob 46 the retraction of the 50 piece 45 will through the crossbar 75 on the under side thereof bear against the lever arm 76 and thereby turn the lever and it, through the flange 80, will operate to throw the slide bar 79 in a forward direction into a position substantially as shown in Fig. 2 where the slide bar is operating to close the slot 24 in the casing and prevent the insertion of a coin until the slide bar has been re-turned to its initial position. The return 55 of the slide bar is obtained when the slide member 30 is retracted for retracting the bolt on turning the knob 56. During such operation the head 29 of the sliding member 30 will engage the flange 80 on the slide bar and thereupon return the slide bar to its initial

position shown in Fig. 1 when a coin can again be inserted through the slot 24.

The lock is preferably provided with a counting device arranged for as follows: 53 represents a counter of ordinary type. This 70 counter is located inside the casing at a point adjacent the rear end of the slide bar 79. The counter is fixed to the interior plate 5 and lies between this plate and the cover 2, the face of the counter showing through 75 a slot 84 in the cover. The counter is operated by an arm 85 which extends through a slot 86 in the plate 5. The end of the arm lies between the flange 80 of the slide bar 79 and a flange 87 on this same bar. When the slide bar is moved forward for closing the slot 24 upon the retraction of the bolt as above explained the flange 87 will contact with the counter arm and thereby actuate the counter. Upon the return of the slide 80 bar 79 to its initial position the flange 80 thereon will engage the counter arm and return it to its initial operative position.

The general operation of the lock is as follows: It will first be assumed that the lock 90 is in place secured to a door closing a room or apartment controlled by the lock. A coin is first inserted. The coin will pass downwardly through the coin chute and come to rest upon the edges 39 and 44, respectively, 95 of the members 30 and 33. Thereupon upon turning the knob 46 the bolt will be moved into a retracted position when the door may be opened. During the operation of retracting the bolt by turning the knob 46 the coin will be lifted into contact with the piece 45 for effecting this operation. Simultaneously with the retraction of the bolt the slide bar 79 will be thrown forward closing the coin slide 24. At the same time the counter will 100 be operated. It will now be assumed that the one turning the knob 46 has released his hold thereon and entered the apartment. Simultaneously with such release the bolt will assume its normal extended or engaging 105 position and the door will become locked, the coin then returning to its initial position contacting with the edges 39 and 44 as shown in Fig. 1. The slide bar 79 will then be left in its engaging position closing the coin slot 24. The one inside the apartment will then 110 apply the latch by turning the thumb piece 60 which operates to prevent the bolt being retracted by turning the exterior knob 46 and also its retraction by turning the interior knob 56. During this period the coin slot remains closed, the previously inserted coin still remaining unreleased. It will now be assumed that the one inside the apartment 115 desires to open the door. This is accomplished by turning the knob 56 for retracting the bolt. In order to turn the knob 56, however, the release of the latch must first be effected by turning back the thumb piece 60, for as previously explained both the 120

115

120

125

130

knobs 46 and 56 are locked against turning by means of the latch. If the latch only controlled the turning of the outer knob 46 then one inside the apartment might force 5 the latch and open the door by turning the interior knob 56 when the door could not be opened from the outside upon the insertion of another coin inasmuch as the knob 46 would still be held against turning by the latch. Inasmuch as the latch locks both knobs against turning, the difficulty referred to is obviated. Assuming now that the latch has been released then the one inside the apartment may open the door by turning the knob 56 which effects a retraction of the bolt. Simultaneously with such retraction the coin is released to fall into the bottom of the casing. At the same time the slide bar 79 will be returned to its initial position 10 leaving open the slot 24 for the insertion of another coin and the arm of the counter will be repositioned for the next operation. In other words, all the parts will then assume their initial positions, the bolt being extended 15 and the door locked.

In case it becomes necessary to get into the apartment when the latch is on, the bolt can be retracted for opening the door through the key-controlled lock 19.

30 Coins deposited in the bottom of the casing are removable through a hinged door 88. This door is held closed by a key-controlled lock 89 preferably of the pin type, the barrel 90 of the lock being provided 35 with an arm 91 which engages the bottom edge 92 of the cover and from which it may be released on turning the barrel by the lock.

Having thus fully described my invention, 40 I claim and desire to secure by Letters Patent of the United States:—

1. In a lock, the combination comprising the lock casing having a coin slot in it, a bolt, movable members inside said casing, means 45 for initially positioning said members to co-operate with one another for receiving and holding a coin deposited within said casing and from which position the members are severally movable for retracting the bolt, means for moving one of said members and coin with it for retracting the bolt, and means whereby as said one member is moved said bolt may be retracted without moving the other of said members.

55 2. In a lock, the combination comprising the lock casing having a coin slot in it, a bolt, movable members inside said casing, means for initially positioning said members to co-operate with one another for receiving and holding a coin deposited within said casing and from which position the members are severally movable for retracting the bolt, means for moving one of said members and coin with it for retracting the bolt, 60 means whereby as said one member is moved

said bolt may be retracted without moving the other of said members, and means for moving the other of said members for reTRACTING said bolt.

3. In a lock, the combination comprising 70 the lock casing having a coin slot in it, a bolt, movable members inside said casing, means for initially positioning said members to co-operate with one another for receiving and holding a coin deposited within 75 said casing, means for moving one of said members and coin with it in the general direction of the other member for retracting the bolt, said one member being adapted when moved as aforesaid to elevate said coin 80 away from the other of said members, and means for otherwise assisting in the retraction of the bolt after the coin has been elevated as aforesaid.

4. In a lock, the combination comprising 85 the lock casing having a slot in it, a bolt, means for retaining said bolt to occupy normally an engaging position, movable members inside said casing, means for initially positioning said members to co-operate with one another for receiving and holding a coin deposited within the casing and from which position the members are severally movable for retracting the bolt, a coin-controlled 90 manually-operated means for moving one of said members and coin with it in the general direction of the other member for retracting the bolt, and means whereby as said one member is moved said bolt may be retracted without moving the other 95 of said members, said last-named means permitting of the return of the coin to its initial position on the release of said manually-operated means and return of the bolt to its 100 engaging position.

5. In a lock, the combination comprising the lock casing having a slot in it, a bolt, means for retaining said bolt to occupy normally an engaging position, movable members inside said casing, means for initially 110 positioning said members to co-operate with one another for receiving and holding a coin deposited within the casing and from which position the members are severally movable for retracting the bolt, a coin-controlled 115 manually-operated means for moving one of said members and coin with it in the general direction of the other member for retracting the bolt, means whereby as said one member is moved said bolt may be retracted without moving the other of said members, said last-named means permitting of the return of the coin to its initial position on the release of said manually-operated means 120 and return of the bolt to its engaging position, and means for moving the other of said members for retracting the bolt and releasing the coin.

6. In a lock, the combination comprising 130 the lock casing, a bolt, separate members ini-

10 tially positioned inside said casing to co-
operate with one another for receiving and
holding a coin deposited within the casing
and from which position the members are
5 severally movable for assisting in the retraction
of said bolt, means assisting in the initial
positioning of one of said members and
operating to move said one member and coin
with it in the general direction of the other
10 10 of said members for retracting the bolt, said
one member being adapted when moved as
aforesaid to elevate the coin away from the
other of said members, and other means ac-
tuated by the elevated coin for then assisting
15 in the retraction of the bolt.

7. In a lock, the combination comprising
the lock casing, a bolt, separate members
initially positioned inside said casing to co-
operate with one another for receiving and
20 holding a coin deposited within the casing
and from which position the members are
severally movable for assisting in the re-
traction of said bolt, means assisting in the
initial positioning of one of said members
25 and operating to move said one member and
coin with it in the general direction of the
other of said members for retracting the
bolt, said one member being adapted when
moved as aforesaid to elevate the coin away

30 from the other of said members, other means
actuated by the elevated coin for then assist-
ing in the retraction of the bolt, means for
initially positioning the other of said mem-
bers, and means whereby the other of said
35 members may be moved from its initial posi-
tion as aforesaid for retracting the bolt and
releasing the coin.

8. In a lock, the combination comprising
the lock casing having a coin slot in it, a
gate controlling said slot, a bolt, movable
members inside said casing, means for ini-
tially positioning said members to co-operate
40 with one another for receiving and holding
a coin deposited within the casing and from
which position the members are severally
movable for retracting the bolt, means for
moving one of said members and coin with
45 it for retracting the bolt, means whereby
as said one member and coin with it is moved
said gate may be closed and said bolt re-
tracted without moving the other of said
members and without releasing said coin,
50 said other member being arranged whereby
it may reopen the gate and release said coin
when moved for retracting the bolt, and
means for moving said other member for re-
tracting the bolt.

ISAAC J. SEGAL.
